Alabama

Application May 1, 1951, Serial No. 224,022

6 Claims. (Cl. 45—24)

1

This invention relates to apparatus for placing a length of material such as textile web under tension for the purpose of performing embroidery or the like.

In greater detail, this invention relates to the art of embroidering designs on textile webs and has for its primary object an apparatus which may be operated by convenient control means to advance a web of material and then place the web under tension. When the web is under tension an operator positioned adjacent the apparatus may proceed to carry out the embroidery operation or another like operation.

A further object of the invention is to provide apparatus in which a continuous web of material may be clamped at a first position and drawing means located at a second position may draw the web in tension against the restraining action of the clamping means.

Further objects and the entire scope of the invention will become more fully apparent from the following detailed description and from the appended claims.

The invention may be understood in detail with reference to the accompanying drawings in which:

Figure 1 shows a side view of apparatus embodying the invention.

Figure 2 shows a top sectional view taken along the line 2—2 of Figure 1.

Figure 3 shows a sectional detail taken along the line 3—3 of Figure 2.

Figure 4 is a view from the front of the apparatus of the above figures.

Figure 5 is a detail view showing a locking arrangement.

Referring now to the drawings, it is the general object of the apparatus to stretch a web of material designated as W throughout an area substantially included beneath the bracket 10 in Figure 1 so that an operator seated to the right of the apparatus as shown in Figure 1 may embroider a design on the web W by use of a conventional embroidering needle held in the hand of the operator.

The apparatus is arranged to be supported on a framework comprising upright standards 12, 14, 16 and 18 which extend from the floor level to any suitable support (not shown) on the overhead of the building in which the apparatus may be located. The uprights 12 and 14 are spaced laterally as best shown in Figure 2 and have mounted horizontally therebetween supporting beams 20 and 22. Beam 20 is attached by any convenient means to the inner side of upright 12 and beam 22 is similarly supported on the inner side of upright 14. This arrangement is best shown in Figure 2. In like fashion between uprights 16 and 18 there are mounted horizontal beams 24 and 26, respectively. Each of the beams 20, 22, 24 and 26 extends rearwardly from the upright standards and terminates in a rear

2

end designated in each case as 28. In addition, the horizontal beams extend forwardly of the upright supports and terminate at a forward end designated 30 in each instance. The forward ends 30 of the horizontal beams may be further supported from the floor by upstanding supports 32 and 34, the supports 32 and 34 being positioned between horizontal beams 20, 22, and 24, 26, respectively.

To receive a supply of the web W there is provided beneath the horizontal support beams a curved hopper panel 36. At the rear of the apparatus the hopper panel 36 is attached by any suitable means to the rear ends 28 of the horizontal support members 22 and 24. At the forward end of the apparatus the hopper panel 36 terminates at a transverse bar member 38. Bar 38 is attached as by bolts 40 to a depending hanger 42 which is attached by bolts 44 and 46 to the underside of horizontal support members 22 and 24. It will be understood from this description of the hopper panel 36 that a considerable length of web W may lie within the thus formed hopper in a folded manner as illustrated in Figure 1.

It will now be assumed that a length of web W is placed within the hopper 36 and an end of the web will be extended from the region of the bar 38 toward the forward ends 30 of the horizontal beams 20, 22, 24 and 26. At the just mentioned position the web W will be trained over the stationary bar 48 of a clamping arrangement which also comprises a movable clamping bar 50. As shown in Figures 1 and 3, the fixed clamping bar 48 consists of a C-shaped channel member having its open side facing the forward end of the apparatus. The bar 48 is further characterized by having its open edges curled inwardly and rearwardly as at 52. The movable clamping bar 50 which cooperates with the fixed member 48 may be of similar C-cross section but will be provided with a liner 54 of a resilient material such as rubber. Liner 54 will be provided with an extruding ridge 56 which will be so positioned as to fit within the curled edges 52 of the fixed clamping bar 48 whenever the movable bar 50 is reciprocated toward the fixed bar. As will be entirely clear from the drawings, if the web W is trained over the open side of fixed clamp 48 and the movable clamp is forcibly moved into engagement with the fixed clamp the web W will be tightly clamped between the liner 54 and the curled edges 52. The clamp is shown in its open position in Figure 1 and in its clamped position in Figure 3.

Fixed clamp bar 48 is arranged to be secured to the horizontal supporting members 20, 22, 24 and 26 by any convenient means such as bolting or welding.

Apparatus of the type now being described may be readily adapted for ganging of a plurality of units in side-by-side relation and in part this

is the reason for providing four uprights and horizontal supporting members as shown in the drawings. With such an arrangement in mind, it becomes clear that the fixed clamp member 48 may be a continuous member extending beyond the outer sides of horizontal supporting members 20 and 22 and may extend for like functional employment in units of tensioning apparatus to either side of the one illustrated.

The movable clamp bar 50 is supported for movement into engagement with clamp bar 48 in the following manner: A pair of horizontally positioned operating rods 58 and 60 are provided, these rods being secured at their forward ends to the movable clamp member 50 adjacent the ends of the latter. As best shown in Figure 2, the movable clamp member 50 will be of such length that its ends will lie approximately at the inner surfaces of horizontal support members 22 and 24 and the edge 56 of liner 54 will lie substantially within these limits. As indicated in Figure 2, the web W will be of somewhat less width than the spacing of operating rods 58 and 60 and, therefore, the latter will not interfere with the web W.

Operating rods 58 and 60 extend through apertures 62 and 64 in the fixed clamp bar 48 and also extend through apertures 66 and 68 in the upright standards 14 and 16. The operating rods 58 and 60 are thus enabled to be reciprocated in a direction which will permit the movable clamp bar 50 to engage the fixed clamp bar 48 as previously described.

To reciprocate the movable clamp bar 50 the operating rods 58 and 60 are respectively provided with sleeves 70 and 72 which are fixed by any suitable means approximately mid-way between the fixed clamp bar 48 and the uprights 14 and 16. Each of the sleeves 70 and 72 is provided with a depending hinge housing 74 which carries a transverse pin 76, the latter extending through the sides of a yoke 78. Welded or otherwise fixedly secured to the lower ends of the arms of yokes 78 are connecting rods 80 which extend from the yokes to a pivotal mounting on a transverse operating shaft 82 which extends across the apparatus substantially the distance between the horizontal supporting members 14 and 16. The shaft 82 is pivotally mounted from the horizontal supports 22 and 24 by means of rocker arms 84 and 86, respectively.

At the left hand side of the apparatus as viewed in Figure 2 there is mounted to the underside of horizontal beams 20 and 22 an air cylinder 88 which is provided with an extending piston rod 90. Fixedly secured to the piston rod 90 is a transverse coupling arm 92 having connected at its end opposite the connection to rod 90 a reverse operating rod 94. The rod 94 is suitably curved to permit clearance below the air cylinder 88 but nevertheless permits a pivotal connection to the previously mentioned shaft 82 adjacent the rocker arm 84.

The air cylinder 88 is provided with an inlet conduit 96 which will permit air under pressure to be introduced into the cylinder 88 to cause the piston rod 90 to be extended from the air cylinder. Accordingly, from the foregoing it will be apparent that if air under pressure is introduced through conduit 96 the rocker arms 84 and 86 are rotated (clockwise in Figure 1 and counterclockwise in Figure 3) so that the operating rods 58 and 60 are reciprocated rearwardly and the movable clamp bar 50 engages the web W between the liner 54 and the fixed clamp bar 48.

A valve 100 is provided which may be operated by a conveniently located knee board 102 to introduce air into conduit 96 as desired. A supply of compressed air is made available at valve 100 through conduit 104 leading from an air supply manifold 106. The knee board 102 and valve 100 may be arranged in one or two different ways to suit the convenience and comfort of the operator. The first arrangement may be that compressed air will normally be available at conduit 96 to maintain the piston rod 90 in the advanced position so that the movable clamp bar 50 is firmly engaged with the fixed clamp bar 48. Actuation of the knee board 102 may then serve to cut off the supply from conduit 104 and to exhaust conduit 96 to atmosphere so that the piston rod 90 will be permitted to retract. By this arrangement knee pressure need be exerted on board 102 only when it is desired to move the web W. The other arrangement may be to have the supply of air to conduit 96 normally cut off requiring pressure on the knee board 102 to advance the piston rod 90 to clamp the web W between clamp bars 48 and 50.

25 A collar 108 is fixedly attached to each of the operating rods 58 and 60 a short distance forward of the upright standards 14 and 16 and a spring 110 is placed between the collars 108 and a washer 112 which lies against the upright standard 14 or 16. The spring 110 has a normal extending position as shown in Figure 1 and will be under compression as shown in Figure 3 when the clamp bars 48 and 50 are engaged. Accordingly, when air pressure in conduit 96 is cut off from supply conduit 104 and 96 otherwise exhausted to atmosphere the springs 110 will cause the operating rods 58 and 60 to retract and open the clamp.

It may be desired to lock the clamp in its open 40 position and to thus positively prevent accidental closing of the clamp by the air cylinder 88. For example, in threading the web W through the clamp it may be desirable from a safety standpoint to insure that the clamp cannot be accidentally closed. To provide for this a locking shaft 114 is rotatably mounted on upstanding bracket arms 116 and 118, these brackets being mounted upon the upper side of horizontal support beam 22. Collars 120 and 122 are provided on shaft 114 these collars being fixedly mounted on the shaft 114 closely adjacent the facing sides of brackets 116 and 118, thereby preventing longitudinal movement of shaft 114 while yet permitting rotation of this shaft. The shaft 114 terminates at a forward end at a position generally adjacent the web clamp and available to the operator. At this forward end an operating handle 124 is provided so that the operator may rotate the shaft 114 to bring a clamping arm 126 into a position whereat a transverse opening 128 in the clamp arm 126 will partially surround the operating rod 58. This detail is best observed in Figure 5. The arm 126 is effective in locking the position of operating rod 58 by reason of a collar 130 which is fixedly secured to the rearward end of rod 58. As best illustrated in Figure 2, when the springs 110 are effective to open the clamp the collar 130 will be in a position closely adjacent the rear surface of upright standard 14 and the clamp arm 126 will be fixedly secured on shaft 114 at such a point that counterclockwise movement of the handle 124 as viewed in Figure 5 will bring the opening 128 over the rearward extremity of rod 58 to prevent the rearward movement of rod 58. Thus,

because of the interconnection between rods 58 and 60 by virtue of shaft 82, the entire clamp will be prevented from closing under the action of air unintentionally introduced into air cylinder 88.

The manner of tensioning the web after being clamped between clamp bars 48 and 50 will now be explained in detail: A main or driven tensioning roller 132 is provided against which an idler roller 134 is engaged. The main roller 132 is mounted in any suitable bearing blocks 136 which are mounted on upright standards 14 and 16. The roller 132 is positioned on the upright standards at a convenient height so that the web W, if trained over the top of roller 132, will assume a slanted position, as shown in Figure 1, to thereby provide the area under bracket 10 whereupon the operator may perform the embroidery operation. The idler roller 134 is mounted for rotation in suitable bearing blocks 138, these blocks being mounted for reciprocating motion on rods 140. The rods extend through suitable apertures in the forwardly extending arms 142 and 144 of brackets 146 which are attached to the forward faces of uprights standards 14 and 16. A collar 148 is fixedly attached to rods 140 between the bracket arms 142 and 144 and a compression spring 150 is provided between the collars 148 and the upper bracket arms 144. Accordingly, it will be apparent that the springs 150 will serve to urge the idler roller 134 into firm engagement with the main roller 132.

In operation, after the web W has been threaded through the previously described clamping arrangement, the end of the web is trained between the top of roller 132 and the bottom of roller 134 and is thereafter lead into the rear portion of the previously described hopper which is defined by the hopper panel 36.

A guide shoe 152 is suitably mounted on the upright standards and positioned just forward of the main roller 132 in a position aligned with the web as tensioned between the rollers and the clamping arrangement. Shoe 152 will serve to support the upper extremity of the tensioned area above the area 10 where the embroidery operation is performed.

The main roller 132 is fixedly mounted on a shaft 154 which extends through the previously mentioned bearing blocks 136 and also at its left hand end, as viewed in Figure 4, extends beyond the bearing block 136 and has fixedly mounted thereon a flat pulley 156 and a ratchet wheel 158. A ratchet pawl 160 is mounted upon a pin 162 which is supported by a triangular-shaped bracket 164 from the forward face of upright standard 12. As viewed in Figure 1, the ratchet pawl 160 will permit the ratchet wheel 158 to rotate counterclockwise but will prevent clockwise rotation.

Power to rotate the main roller 132 is provided from a belt 166 which supplies power from any convenient source (not shown) to a pulley 168 mounted near the upper extremity of the uprights standards. The pulley 168 may be fixedly mounted on a shaft 170 and a second pulley 172 may be also fixedly mounted on shaft 170 and be aligned with the previously mentioned pulley 156 on shaft 154, so that a belt 174 may be arranged to run over the pulleys 156 and 172. The pulley 168 will be driven in a counterclockwise direction as viewed in Figure 1, the ratchet pawl 160 being so oriented as to permit this rotation. Accordingly, it will be apparent that when and if the

belt 174 is tensioned to transmit power the roller 132 will rotate counterclockwise and the web W will be placed under tension when the clamping members 48 and 50 are operated into engagement.

To control the application of tensioning power to the roller 132 there is provided a belt-tightening idler pulley 176 which is rotatably mounted on a bell crank lever 178 having an upwardly extending arm 180 on which the pulley 176 is mounted and having a forwardly extending arm 182. The bell crank is mounted for pivotal movement at pivot pin 184, the latter pin being retained in angle brackets 186 and 188 mounted on upright standards 12 and 14, respectively. Adjacent the forward end 182 of the bell crank 178 there is pivotally mounted a connecting link 190 which extends downwardly between the horizontal beams 20 and 22 and terminates at its lower end at a pivot pin 192, which pin serves to pivotally attach arm 190 with a rocker arm 194. Rocker arm 194 is pivotally mounted at its rearward end by means of a pivot pin 196 to a suitable bracket 198 mounted on the forward surface of upright standard 14. An air cylinder 200 is mounted on the underneath surfaces of horizontal support beams 20 and 22 and a piston rod 202 extending downwardly from air cylinder 200 is arranged to engage with the rocker arm 194 approximately midway between the ends of the latter. The air cylinder 200 is provided with an air supply conduit 204 which leads from a foot control valve 206. A supply of air under pressure for the valve 206 is available through a conduit 208 leading from the previously mentioned air supply manifold 106. The operator may actuate the foot valve 206 to supply air under pressure through the conduit 204 to the cylinder 200. When this occurs the piston rod 202 will be extended from the air cylinder and the linkage comprising arms 194-190 and bell crank 178 will move the idler pulley 176 against the belt 174 to tension the latter and thus cause roller 132 to move counterclockwise as viewed in Figure 1. Assuming the clamp bars 48 and 50 have been firmly engaged under the action of air cylinder 88, the web W will be moved between the rollers 132 and 134 and tension will be established in the web depending upon the power available from belt 166 and the pressure exerted between belt tensioning pulley. The ratchet pawl 160 will permit the roller 132 to take up the web W until a predetermined tension has been reached. The degree of tension will be adjusted to a predetermined amount by any of several apparent means such as by arranging the air pressure in cylinder 200 to have an upper limit so that the belt 174 will slip after the tension in web W prevents further rotation of the roller 132. After the desired tension has been obtained the operator may release the foot control valve 206 and the pawl 160 will serve to maintain the roller in its advanced position notwithstanding the fact that the pressure of roller 176 is released.

Movement of the bell crank 178 under the action of air cylinder 200 may be conveniently limited by a post 210 mounted on the horizontal support members 20 and 22 and being provided with a suitably padded upper end 212. A tension spring 214 may extend between a pin 216 on the arm 182 of bell crank 178 and a suitable supporting bar 218 mounted near the upper extremity of the apparatus.

From the foregoing it will be apparent that by this invention there is provided a novel arrangement in which a length of material such as tex-

tile web may be readily advanced and then tensioned in various predetermined positions by conveniently located foot and/or knee controls whereby the operator need not lay aside his embroidery needle device or the like in order to properly tension the material in a new position. Normally, in the embroidery of textile web the web will have already printed thereon various designs which the embroidery operator is to follow. Accordingly, after one area has been embroidered the operator need only release the clamping arrangement by the knee control and then operate the foot control to advance the web. When the web has reached the correct advanced position, as indicated by the location of the printed designs within the area under bracket 18 the knee control is operated to clamp the material. The foot control is then employed to bring the web into its tensioned condition whereupon the controls require no further attention while the operator goes about the embroidery operation.

It is expected that after reading the foregoing specification many other embodiments of the invention will become apparent. Therefore, it is not intended that the foregoing detailed description limit the invention. The true scope of the invention is to be determined from the appended claims.

We claim:

1. In tensioning apparatus, means located at a first position for clamping a web of material, means located at a second position for drawing the web in tension against the restraining action of the clamping means, separately operable means for advancing the drawing means, and means comprising unidirectional motion means operatively associated with the drawing means for retaining the drawing means at a predetermined advanced position to maintain tension in the web of material.

2. In material tensioning apparatus, clamping means located at a first position for clamping a web of material, drawing means located at a second position for drawing the web in tension against the restraining action of the clamping means, separately operable means for advancing the drawing means in a tensioning direction, and unidirectional motion means operatively associated with the drawing means for retaining the drawing means in predetermined advanced positions to maintain predetermined tension in the web of material.

3. In tensioning apparatus, a supporting framework, fixed and movable clamp bars located at a first position on the framework, means for moving the clamp bars into engagement with one another to clamp a web of material therebetween, drawing means including interengaging main and idler rollers located at a second position on the framework, means for rotating the rollers for drawing a web of material in tension against the restraining action of the clamping bars between which the web is clamped, means for rotating the drawing rollers in a web tension direction, and ratchet pawl means operatively associated with the main drawing roller for retaining the drawing rollers in a predetermined advanced position to maintain predetermined tension in the web of material.

4. In tensioning apparatus, a supporting framework, a hopper chamber in the framework for retaining a supply of textile web upon which embroidery is to be performed, horizontal beams included in the framework, a first web clamping bar fixedly mounted on the horizontal beams, a second web clamping bar, operating rods hav-

ing ends thereof fixedly secured to the second clamping bar, vertical standards included in the framework, apertures in the standards and in the first web clamping bar for slidably receiving the operating rods, a pneumatic cylinder having a piston, means interconnecting the piston and the operating rods, and means for selectively supplying air under pressure to the cylinder to react against the piston to move the second web clamping bar into engagement with the first bar, whereby a length of web lead from the hopper chamber and between the first and second clamping bars may be clamped therebetween.

5. In tensioning apparatus, a supporting framework, a first web clamping bar fixedly mounted on the framework, a second web clamping bar, operating rods having ends thereof fixedly secured to the second clamping bar, means on the framework for slidably receiving the operating rods, means for moving the operating rods for engaging the first web clamping bar with the second bar, a web advancing roller rotatably mounted on the framework, an idler roller also mounted on the framework and resiliently urged against the advancing roller, power means for applying rotational power to the advancing roller, and unidirectional motion means for permitting rotation of the advancing roller in only one direction, whereby a web of material extending between the clamping bars and then between the rollers may be tensioned over the length of the web between the bars and the rollers to permit embroidery or the like to be performed on the web.

6. In tensioning apparatus, a supporting framework, a hopper chamber in the framework for retaining a supply of textile web upon which embroidery is to be performed, horizontal beams included in the framework, a first web clamping bar fixedly mounted on the horizontal beams, a second web clamping bar, operating rods having ends thereof fixedly secured to the second clamping bar, vertical standards included in the framework, apertures in the standards and in the first web clamping bar for slidably receiving the operating rods, a pneumatic cylinder having a piston, means interconnecting the piston and the operating rods, means for selectively supplying air under pressure to the cylinder to react against the piston to move the second web clamping bar into engagement with the first bar, a web advancing roller rotatably mounted on the standards, an idler roller also mounted on the standards and resiliently urged against the advancing roller, power means for applying rotational power to the advancing roller, and unidirectional motion means for permitting rotation of the advancing roller in only one direction, whereby a web of material extending between the clamping bars and then between the rollers may be tensioned over the length of the web between the bars and the rollers to permit embroidery or the like to be performed on the web.
